UNITED STATES PATENT OFFICE.

WILLIAM M. BAXTER, OF FORT WAYNE, INDIANA, ASSIGNOR, BY MESNE ASSIGNMENTS, TO THE WAYNE HOME EQUIPMENT COMPANY, OF FORT WAYNE, INDIANA, A CORPORATION OF MARYLAND.

MEANS FOR CONTROLLING THE FLOW OF ALL FLUIDS IN AN OIL-BURNER APPARATUS.

Application filed August 16, 1926. Serial No. 129,439.

My invention relates to oil burners and particularly to means for controlling the flow of all fluids in an oil burner apparatus.

When an oil burner is shut down air must not flow from outside the furnace to the burner nozzle or the combustion chamber will be quickly cooled; the flow of the gas must be regulated so that only a sufficient quantity passes from the source of supply to the burner nozzle to maintain the pilot light, and the flow of fuel must be shut off so that the burner nozzle and the combustion chamber will not be flooded. These flows are inter-related and one object of this invention is to provide combined means for regulating all these flows.

Another object of my invention is to provide means for preventing the siphoning of fuel oil from the source of supply to the burner tip regardless of the position or altitude of the supply tank.

Another object of my invention is to provide means for controlling the flows of fuel oil, air and gas to an oil burner by the pressure of the fuel oil flowing through the system.

Another object of my invention is to provide highly concentrated means for regulating all these flows for only a very limited space is available in oil burning apparatus for domestic and many uses.

Another object of my invention is to provide a rugged mechanism such as will not require the services of an expert attendant and which when properly adjusted will operate without supervision, as few householders will have available expert attendants nor will they wish to be annoyed by requirement for service from anyone.

Another object of my invention is to provide comparatively inexpensive control means of the character indicated, a very important feature of domestic installations.

This and other objects will be more apparent from the following complete description of the invention.

In the particular embodiment of my invention selected for illustration:—

Figure 1 is a side elevation of an oil-burner assembly including combined air, gas and fuel oil controlling means, part of the housing being cut away and in section to show the fan damper.

Fig. 2 is a top plan view of the controlling means with the damper omitted. 55

Fig. 3, a detail, is the lever through which both valves and the damper are actuated by the pressure of the fuel oil on the sylphon bellows.

Fig. 4 is an elevation of part of the controlling mechanism with the sylphon bellows and gas valve shown in axial section taken on line 4—4 of Fig. 2. 60

Fig. 5, a detail, is an elevation showing in axial section the oil valve lifting shaft and attendant parts shown at the top of and taken on line 5—5 of Fig. 2. 65

Fig. 6, a detail, is a vertical axial section through the gas valve and attendant parts, taken at 90° from the view shown in Fig. 4 70 and on the line 6—6 of Fig. 2.

Fig. 7 is a vertical axial section on the line 7—7 of Fig. 2 through the non-siphoning oil valve and attendant parts.

Fig. 8, a detail, is a perspective of the oil 75 valve lifting yoke.

Fig. 9 is an exterior side view of the oil valve plunger shown in horizontal instead of vertical position, and

Fig. 10 is an end view of the same from 80 the small end.

Referring now to the drawings, T is a tripod frame to which the control mechanism is secured and upon which the fan housing F is mounted, being secured thereto by screws 85 f¹. A motor M surmounts the fan housing and is secured to it. The damper f is mounted in the air delivery pipe f² of the fan housing, being secured in position and adapted to oscillate on a pivot f³, to which it is fixed by 90 means of set screw f⁴. The projecting lug f¹ forms a lever for actuating the damper and to this lever is secured by pin f⁵ a connecting bar f². The damper is opened by upward pressure on the connecting bar f² which is pivoted by pin f⁵ to weighted lever D hereinafter to be described. The power chamber within which is mounted the sylphon bellows a¹, and a fuel oil chamber which contains the oil valve, are preferably formed from a single casting. 95 That portion of this casting which forms the casing for the power chamber is designated as 1^a and has a chamber a² and a cover plate a. Within this chamber is mounted a sylphon bellows pressure valve assembly consisting of 100 a sylphon bellows a¹ with a top head a⁴ ex-

tended at its sides so as to have its edges clamped between the top of the chamber casing 1^A and the bottom of the cover plate a by screws a^6 . Both the cover plate a and the top head a^4 are pierced axially to receive the plunger a^2 which reciprocates vertically therethrough. This plunger a^2 is secured to the sylphon bottom head a^3 by pin a^5 and its lower portion is extended to form a guide rod seated in the axial bore a^8 of the boss a^7 on the inner side of the bottom of the casing 1^A . The sylphon is hermetically sealed to its top head a^4 and to its bottom head a^3 so that when the fuel oil enters this chamber and a sufficient pressure is built up to compress the sylphon bellows the plunger a^2 is forced upwardly. To one side of the pressure chamber casing 1^A is formed the flange 1^F through holes f^9 in which, by screws g^1 , this portion of the control mechanism is secured to the tripod support T . At another side of the pressure chamber casing 1^A is formed a non-siphoning fuel oil valve casing 1^B . A cored passage 1^P connects the chamber of 1^A with the chamber of 1^B . The chamber of 1^B is designated as b^{11} and has inlet b^{10} and outlet b^{12} . The casing 1^B is bored vertically at b . A valve plunger b^1 with capillary sealing grooves b^2 , relief groove b^{15} and top flange b^3 is axially bored at b^4 from the top nearly its entire length to receive valve spring s , and this valve plunger is adapted to reciprocate in the bore b . The lower end of the valve plunger b^1 is undercut at b^5 to receive a soft metal seating plug b^6 which has a groove b^7 adapted to co-act with the oil valve seat b^9 on the renewable valve seat plug b^8 which is threaded into the casing 1^B . The casing 1^B is provided with a threaded cap b^{13} axially bored to receive the top end of the spring s . In the casing 1^B above the plunger bore is formed a chamber b^{14} and within this chamber is located a valve lifting yoke b^{16} secured to a shaft C journaled at its inner end c in the wall of the casing 1^B , passing outwardly through stuffing box c^1 , carrying on its outer portion a lever c^2 fixed to said shaft, and on its outer end a lever D with a weight d pivoted on said shaft. Through a fork d^1 extends a pin f^8 which acts as a pivot for the lower end of the connecting bar f^2 . The lever c^2 has on its under side a boss c^3 against which the top of the plunger a^2 impinges. The upward movement of the lever c^2 is limited by the adjustable stop c^4 and its downward movement is limited by the adjustable stop c^5 threaded at c^6 through said lever. On one side of the lever c^2 is formed a lug c^7 and upon this lug the lever D rests. The gas valve casing g is formed in the upper part of a bracket G which is secured by screws g^1 to the cover plate a . The casing g has a gas inlet g^2 , a gas outlet g^3 and bleed port g^4 to admit a small quantity of gas continually so as to maintain the usual pilot light adjacent to the burner. Any greater flow of gas through

the casing g is controlled by the poppet valve g^5 with guiding member g^6 adapted to reciprocate in the bore g^7 and normally held to its seat by coiled spring s^1 . This spring is adapted to be opened by the upward pressure of the valve stem g^8 which passes through the stuffing box g^9 and is actuated by the lever c^2 whenever said lever is raised.

Fuel oil is taken into the system to the pump P through the pipe p and the excess is returned to the storage tank through the pipe p^1 . The fuel oil supplied to the burner is pumped by pump P through the pipe p^3 through the inlet b^{10} into the chamber b^{11} , and after sufficient pressure is built up in the power chamber a^9 to compress the sylphon, raise the lever c^2 , rotate the shaft C , and through the yoke b^{16} raise the valve plunger b^1 , the fuel oil flows from the outlet b^{12} through the pipe p^2 to the spray tip in the combustion chamber (not shown).

As in all such apparatus, a thermostat is used to shut off the power and as soon as the motor stops running the pump is out of operation. In this apparatus when there is no pressure exerted on the fuel oil due to the stopping of the pump, the valve plunger b^1 rests upon its seat b^9 , thus closing the passage for the flow of oil to the spray tip. It therefore prevents any siphoning of oil from the supply tank to the tip regardless of the position or altitude of such supply tank.

Special precaution has been taken to ensure the functioning of this apparatus. The operation of the damper controlling the air flow and of the gas valve controlling the flush flow of gas to the burner are dependent upon the functioning of the apparatus in the power chamber, and whenever the motor and pump are shut down the sylphon returns to expanded position, this being doubly ensured, as such return is provided by the downward pressure of the spring s and also by the downward pressure of the weighted lever D . As the return of the sylphon to expanded position shuts off the flow of the oil to the burner there never can be any flooding of the burner. If the spring s should set or break the weighted lever D alone would shut off the oil supply, and if by any possibility the weighted lever D should be held up and fail to descend the pressure of the spring s alone would shut off the oil supply.

Many changes may be made in the means shown for carrying my invention into effect without departing from the spirit of the invention, and I claim all forms covered by the claims.

I claim as my invention and desire to secure by Letters Patent of the United States:

1. In combination with an oil burning system comprising a burner, a fuel oil reservoir, a pump for forcing oil under pressure from said reservoir to said burner, fuel oil connections including a valve to control the flow of

- oil from said pump to said burner, gas connections including a valve to control the flush flow of gas to said burner, a fan and connections to supply air to said burner, and a 5 damper in said connections to control the flow of air therethrough; inter-related means operable by the pressure of the fuel oil flowing through the system for synchronously actuating the said fuel oil valve, said gas valve and 10 said damper.
2. In combination with an oil burning system comprising a burner, a fuel oil reservoir, a pump for forcing oil under pressure from 15 said reservoir to said burner, fuel oil connections including a valve to control the flow of oil from said pump to said burner, gas connections including a valve to control the flush flow of gas to said burner, a fan and connections to supply air to said burner, and a 20 damper in said connections to control the flow of air therethrough; means operable by pressure of the oil so pumped to said burner, and inter-related means operable by said pressure operated means for synchronously ac- 25 tuating said fuel oil valve, said gas valve and 30 said damper.
3. In combination with an oil burning system comprising a burner, a fuel oil reservoir, a pump for forcing oil under pressure from 35 said reservoir to said burner, fuel oil connections including a valve to control the flow of oil from said pump to said burner, gas connections including a valve to control the flush flow of gas to said burner, a fan and connections to supply air to said burner, and a 40 damper in said connections to control the flow of air therethrough; pressure operated means including a circumferentially corrugated longitudinally expansible sleeve axially compressible by pressure of the oil so pumped to said burner, inter-related means operable by said pressure operated means for synchronously actuating said fuel oil valve, said gas valve and said damper.

In testimony whereof I have hereunto set my hand.

WILLIAM M. BAXTER.
